UNITED STATES PATENT OFFICE.

DOUGLAS D. McEARLY, OF CLINTON, MISSISSIPPI.

IRRIGATING APPARATUS.

1,124,161.

Specification of Letters Patent.

Patented Jan. 5, 1915.

Application filed December 2, 1913. Serial No. 804,258.

To all whom it may concern:

Be it known that I, DOUGLAS D. McEARLY, a citizen of the United States, residing at Clinton, in the county of Hinds and State 5 of Mississippi, have invented new and useful Improvements in Irrigating Apparatus, of which the following is a specification.

This invention relates to certain new and useful improvements in irrigating apparatus 10 of the overhead type, and particularly to pumps therefor.

One object of the invention is to provide an overhead irrigating system embodying a novel construction of double-acting pump 15 for supplying a continuous stream of water to the sprayers or discharge nozzles.

Another object of the invention is to provide a pump of the character described which is simple of construction, reliable and 20 efficient in action, which comprises few parts liable to get out of order, and which has an even irrigating pumping action.

The invention consists of the features of construction, combination and arrangement 25 of parts herein fully described and claimed reference being had to the accompanying drawings in which:—

Figure 1 is a side elevation showing the application of the invention to an irrigating system, a portion of which is herein disclosed. Fig. 2 is a plan view thereof. Fig. 3 is a vertical transverse section on the line 3—3 of Fig. 2. Fig. 4 is a vertical longitudinal section through the pump. Fig. 5 is 35 a horizontal section on the line 5—5 of Fig. 4. Fig. 6 is a view of the double pump piston removed, with parts appearing in section. Fig. 7 is a detail section on the line 7—7 of Fig. 6. Fig. 8 is a view showing the 40 construction of one of the check valves.

In the present disclosure, I have shown the application of my invention to an irrigating apparatus of the overhead type embodying a main distributing pipe 1, a supply pipe 2 communicating therewith, and a series of parallel delivery pipes 3 leading from the delivery pipe and provided at intervals with depending sprayers or discharge nozzles, the pipe being suitably supported from and at a desired elevation above the ground or field to be irrigated. The pipe 2 is in communication with a double-acting pump 5, by which, when the apparatus is in service, a continual flow of water is 50 supplied through the distributing and delivery pipes to the discharge nozzles. This

pump is preferably composed mainly of piping and comprises a pair of working cylinders 5' and 6 arranged in longitudinal alignment and coupled at their inner or 55 proximate ends by a bearing sleeve 7, provided with an outlet nipple or pipe 8 communicating with the supply pipe 2, said sleeve being also provided with suitable bearings for a drive shaft 9, which extends 60 outwardly through a stuffing box 10.

The outer ends of the cylinders 5 and 6 are connected by companion elbows 11 and 12 with elbows 13 and 14, which are connected with the outer ends of a pair of 65 aligned suction pipes 15 and 16, united at their inner ends by a forearmed coupling 17 with which communicates an inflow or suction pipe 18, communicating in practice with a suitable source of water supply, the coupling 17 being connected with the sleeve 7 by a suitable reinforcing member 19, whereby the parts of the pumping mechanism above described are properly tied and braced together. 70

The sleeves 11 and 12 are respectively coupled to the elbows 13 and 14 by sets of connections, each comprising a threaded coupling pipe or nipple 20 and a coupling member or bushing 21, the said bushings 21 75 projecting into the sleeves 11 and 12 and having their upper portions provided with guides 22 and formed to provide valve seats 23 for gravity closing check valves 24 and 25, which are vertically movable on the respective guides. Each valve is adapted to open upwardly on the suction stroke of the associated piston member, for the inflow of water to the associated cylinder, on the reverse stroke of the piston member to close 80 by gravity against its seat to prevent the further influx of water and to allow the water drawn in to flow through such piston member for discharge through the outlet 85 90 95 95.

The double piston 26 operating within the 100 cylinders comprises a substantially oblong rectangular plate, the body portion 27 of which is slidably mounted in the sleeve 7, and the end portions 28 and 29 of which are slidably movable in the cylinders 5 and 6. The body portion 27 is formed with an elongated longitudinal slot or opening 30 having upper and lower sets of rack teeth 31 and 32 which are adapted to mesh alternately with the teeth 33 of a mutilated gear 34 fixed to the shaft 9, which is rotated continuously from any suitable source of power. 105 110

In the rotation of the mutilated gear the piston is alternately reciprocated in opposite directions, as will be readily understood. The gear, as shown, is preferably of the 5 grooved or flanged type, to maintain a constant engagement with the sides of the body 27 and prevent the teeth from slipping laterally out from engagement with each other.

The portions 28 and 29 of the piston plate 10 or frame carry piston heads or members 35 and 36, which operate in the respective cylinders 5 and 6, each of said piston members being of annular form to provide a water 15 passage 37 and annularly grooved to receive suitable packing 38. Each end 28 and 29 of the piston frame is slotted or bifurcated to provide a pair of guide arms 29 terminating in threaded shanks 40 which pass through openings in the associated piston head and 20 are provided with clamping nuts 41, whereby said piston head is detachably secured in position. The inner face of each piston head forms a valve seat for a check valve 42, which comprises a plate movable in the 25 space between the guide arms 39 and having notched portions 43 slidably engaging said arms, whereby the valve is guided and slidably mounted for inward movement to open the passage 37 and outward movement to close said passage. The body of the piston 30 plate or frame is formed with openings 44 in which slide stems 45 fixed to the valves, and associated with which are coiled springs 46 adapted under their expansive energy to 35 hold the valves normally closed.

From the foregoing description, it will be understood that in the operation of the apparatus the piston will alternately draw charges of water in through the pipes 15 40 and 16 and discharge the same in a continuous stream through the pipe 8 to the pipes of the irrigation apparatus. On the inward or suction stroke of each piston member, it will be evident that the check valve controlling the passage therein will be held 45 closed, while the check valve in the associated inflow conductor will open, whereby a charge of water will be drawn into the cylinder, that on the outward stroke of the piston the check valve in the inflow conductor 50 will be closed, while the check valve of the piston will open under pressure to allow the water to flow through the passage in

the piston, which water is discharged on the ensuing inward or suction stroke of the piston member. It will also be apparent that the pump construction described provides for the ready assemblage, disassemblage, repairs and renewal of parts, while, owing to the simplicity of the piston and valve mechanism, as well as the construction of the piston *per se*, an even and regulated action of the pump is insured, the advantage of which in an irrigating apparatus will be manifest.

I claim:—

1. A pump of the character described comprising a pair of communicating cylinders having a common outlet and separate check-valved inlets, a piston comprising a body having bifurcated ends moving in the respective cylinders and provided with guide arms, piston members secured to the arms of the bifurcated ends of the piston body and movable in the respective cylinders, each of said piston members having a water passage, spring closed check valves controlling said passages and slidably engaging the guide arms, and rack and pinion mechanism for alternately shifting said piston in opposite directions. 70

2. A pump of the character described comprising a pair of communicating cylinders having a common outlet and separate check-valved inlets, a piston comprising a body plate having a longitudinal slot with rack teeth at opposite sides thereof, and having bifurcated end portions movable in the respective cylinders and provided with guide arms terminating in stems, annular piston members secured to the stems and movable in the respective cylinders, each of said piston members having a water flow passage, spring-controlled check valves controlling the passages in the piston members and having slotted portions slidably engaging the guide arms, a rotary shaft, and a mutilated pinion actuated by said shaft and adapted to alternately engage the toothed portions of the piston body to alternately shift the piston in opposite directions. 90

In testimony whereof I affix my signature in presence of two witnesses.

DOUGLAS D. McEARLY.
